UNITED STATES PATENT OFFICE

115,988

DESIGN FOR A BOLERO

Morris Wartsky, New York, N. Y.

Application January 6, 1939, Serial No. 82,194

Term of patent 3½ years

To all whom it may concern:

Be it known that I, Morris Wartsky, a citizen of the United States and residing in Manhattan, in the city, county, and State of New York, have invented a new, original, and ornamental Design for a Bolero, of which the following is a specification, reference being had to the accompanying drawings, forming part thereof, wherein

Fig. 1 is a front view of a bolero with the corners turned back showing my new design.

Fig. 2 is a rear view thereof.

Fig. 3 is a front view of the bolero shown in Fig. 1 with one corner turned down.

The characteristic feature of the design resides in the specific embroidery on each side of the relatively wide folded band binding the neck and outer edges of the specific bolero, as shown.

I claim:

The ornamental design for a bolero, substantially as shown and described.

MORRIS WARTSKY.
